Huntsville, Ala.

Filed Aug. 28, 1961, Ser. No. 66,510

Term of patent 14 years

(Cl. D81—10)

FIG. 1

FIG. 2

FIG. 3

FIG. 4

FIG. 1 is a perspective view of a heater casing showing my new design.

FIG. 2 is a front elevational view.

FIG. 3 is a side elevational view; and,

FIG. 4 is a top plan view.

The dominant features of my design reside in the portions shown in full lines. It is to be understood that the screening, fragmentarily illustrated in the several views, covers the entire top, sides and front of the portion indicated.

I claim:

The design for a heater casing, as shown and described.
